CLAIM

The ornamental design for a radiator with joint as shown and described.

DESCRIPTION

FIG. 1 is a front perspective view of a radiator with joint embodying our new design;

FIG. 2 is a front elevational view thereof;

FIG. 3 is a rear elevational view thereof;

FIG. 4 is a right side elevational view thereof;

FIG. 5 is left side elevational view thereof;

FIG. 6 is a top plan view thereof; and,

FIG. 7 is a bottom plan view thereof.

Portions of the article that are not shown form no part of the claimed design, including the appearance of any portion of the article between the break lines. Any broken line illustration of environmental structure in the drawings is not part of the design sought to be patented.
